CLAIM

The ornamental design for an ice skate blade guard, substantially as shown and described.

DESCRIPTION

FIG. 1 is a perspective view of an ice skate blade guard showing my new design;

FIG. 2 is a side elevational view of the side not shown in FIG. 1;

FIG. 3 is a top plan view;

FIG. 4 is a bottom plan view;

FIG. 5 is an end elevational view, the opposite end being a mirror image thereof;

FIG. 6 is a sectional view taken along the line 6—6 of FIG. 2; and

FIG. 7 is a perspective view of an alternative embodiment thereof.
